WORK DOG

Charles D. Mack, Cleveland, Ohio

Application July 9, 1938, Serial No. 218,426

11 Claims. (Cl. 82—41)

This invention relates to work-holders, clamps and vices and particularly to those tools known as work-dogs used for holding material during a grinding, drilling or polishing operation.

5 An object of the invention is to provide a device that will conveniently grip round objects of different sizes, and which is easily and quickly attached or removed from the object being held.

Another object of the invention is to provide 10 a device of this type with an adjustable clamping means which cooperates with a lever operated toggle overthrow catch.

These and other objects and features of the 15 invention will become clearer from the study of the following specification and accompanying drawing wherein like parts are designated by like reference characters and in which:

Figure 1 is a side view of the device holding a piece of material on a machine;

20 Figure 2 is a front view of Figure 1;

Figure 3 is a side view of the device only in its open position;

Figure 4 is a sectional view of the Figure 3 taken along the lines 4—4 of that figure;

25 Figure 5 is a side view of a modified form of the device with parts of the tool broken away;

Figure 6 is a sectional view of the modified form taken along the lines 6—6 of the Figure 5; and

30 Figure 7 is a sectional view of the modified form taken along the lines 7—7 of the Figure 5.

The comprehensive views of the Figures 1 and 2 show a part of an automatic machine face plate 11 with its projecting peg 12, its live center 13, a piece of material 14 to be worked upon and the device constituting this invention holding the work in the machine.

The work-dog herein claimed is made of metal. Its elementary parts consist of a ring or collar 15 to which there is attached or made with the handle 16. The collar 15 has a radial hole 17 through it and which was drilled at about a 30° angle above the handle 16. The handle 16 is hollow, has a pair of lateral holes for retaining the pin 19, a small hole in its under side for engaging the tension means 27 and an internally threaded end 28 for engaging an adjusting screw 29.

The lever or cam member 18 is somewhat triangular in shape, is thin enough to fit nicely between the side walls of the handle 16 and has one of its corners pivoted in the handle by the pin 19 near the collar 15.

A second corner of the cam 18 has a small slot 21 in which there is pivoted the floating pin 22.

This latter pin 22 fits and moves in the aforementioned radial hole 17 in accordance with the movement of the cam 18.

There is also pivotally attached to the third corner of the cam 18 the lever 23 of the toggle mechanism. The lever 23 is bent slightly so that its movable fulcrum point 24 may be overthrown or shifted past the line between the power and the resistance or as is illustrated here, between the lever handle 25 and the cam 18. When 10 the handles 16 and 25 are separated as illustrated in the Figure 3 the pin 22 is drawn outwardly of the radial hole 17 in the collar 15; and when they are closed as shown in the Figure 1 the pin 22 is projected inwardly and into the 15 opening 26 of the said collar. The collar 15 and the pin 22 act substantially the same as a pair of jaws or like a special vise for gripping material.

A small coil extension spring 28 is attached to the cam 18 and to the handle 16 to normally 20 draw the pin 22 outwardly of the collar opening 26 so that the said opening is clear for the insertion of new work therein.

The end 28 of the handle 16 is internally threaded as shown to receive the externally 25 threaded adjusting bolt 29. This bolt 29 moves lengthwise in the handle and has a small ball end 30 which engages the cupped end 33 of the arm 32 which arm is swivelly connected to the lever 23. Advancing the ball end 30 by the turning of 30 the bolt 29; the arm 32, the lever 23, and the cam 18 are correspondingly moved forward with the result that the pin 22 is projected further into the collar opening 26. Likewise causing the ball end 30 to recede, withdraws the pin 22 from the 35 collar 15. A simple lock nut 31 fixes the position of the ball end 30 so that the work 14 can be speedily and conveniently handled. Work of different sizes or diameters can be accommodated by simply adjusting the bolt 29.

The modified design illustrated in the Figures 5, 6 and 7 is substantially the same as the one previously described. Its primary distinction lies in the floating pin or wedge 36 in the chordal hole 35 which is substituted for the projecting 45 pin 22 in the radial hole 17. The wedge 36 extends clear through the collar 15 and projects outwardly therefrom for a short distance. The projecting end 37 is convenient for quickly removing the device from the work as a slight tap 50 on that end quickly loosens the wedge.

The wedge 36 itself is connected to the cam 18 in the same manner as the pin 22 is connected to the cam 18. A part of its circumferential surface; that part 38 which moves in the collar open- 55

ing 26 and contacts the material 14 is ground flat and tapered slightly to give it a proper wedge action.

The modified design as illustrated also shows 5 a small leaf type spring 27a for retaining the cam 18 in its normal or open position instead of the coil spring 27. Either type of spring is suitable for either style of device.

The device, while shown in its preferred forms 10 may be modified in other sizes by those skilled in the art. While certain specific terms and definite language have been used, it must be understood that the invention as described is illustrative rather than restrictive, as no limitations 15 are intended other than those imposed by the scope of the appended claims.

I claim:

1. A work-dog, comprising in combination, a collar having a chordal hole therein and a handle attached thereto, a wedge within the chordal hole, and a tensional adjustable toggle mechanism for moving and positioning the said wedge in the said chordal hole.
2. A work-dog, comprising in combination, a 20 collar having a radial hole therein and a handle attached thereto, a tensioned pin within the radial hole, and an adjustable toggle mechanism attached to the handle for moving and positioning the said pin in the said radial hole.
3. A work-dog, comprising in combination, a 25 collar, a cam attached to the collar, a pin projecting through the collar operable by the cam, and a toggle mechanism attached to the collar and the cam for operating the said pin.
4. A work-dog, comprising in combination, a 30 collar having a radial hole therein, a cam attached to the collar, a pin projecting through the radial hole floatingly attached to and operable by the said cam, and a tensional adjustable toggle mechanism attached to the collar and the cam for moving and positioning the said pin in the said radial hole.
5. A work-dog, comprising in combination, a 35 collar having a chordal hole therein and a handle attached to the said collar, a cam attached to

the handle, a tensioned wedge projecting through the hole and floatingly attached to the said cam, and an adjustable toggle mechanism attached to the handle for moving and positioning the said wedge in the said hole.

6. A work-dog, comprising in combination, a 40 collar having a chordal hole therein, a cam attached to the collar, a wedge projecting through the hole operable by the cam, and a toggle mechanism for moving and positioning the said wedge in the said hole.

7. A work dog, comprising in combination, a 45 member substantially encircling the work, a handle on the member, a part having a pin hinged thereto, the said pin movable transversely in the 50 said member, and an adjustable toggle mechanism, carried by the handle and operable to move the said part.

8. A work-dog, comprising in combination, a 55 collar, a handle attached to the collar, a cam attached to the handle, a pin attached to the cam, and an adjustable toggle mechanism attached to the said handle for operating the said cam.

9. A work-dog, comprising in combination, a 60 25 collar having a hole therein, a handle attached to the collar, a lever attached to the handle, a pin attached to the lever moveable in the said hole in the collar, and an adjustable toggle mechanism attached to the said handle for operating the said lever.

10. A work-dog, comprising in combination, a 65 collar having a handle attached thereto, a lever attached to the handle, a pin floatingly attached to the lever and moveable within the collar, and an adjustable toggle mechanism attached to the said handle for operating the said lever.

11. A work-dog, comprising in combination, a 70 collar having a radial hole therein and a handle attached thereto, a lever attached to the handle, a pin floatingly attached to the lever and moveable within the radial hole, and an adjustable toggle mechanism attached to the said handle for operating the said lever.
